UNITED STATES PATENT OFFICE

GEORGE H. ANGERT, OF CINCINNATI, OHIO, ASSIGNOR TO ANGERT BROTHERS, A CO-PARTNERSHIP COMPOSED OF ARTHUR C. ANGERT AND GEORGE H. ANGERT, OF CINCINNATI, OHIO

TABLE

Application filed March 16, 1929. Serial No. 347,568.

This invention relates to improvements in extension tables, and more especially to tables of this type having a leaf designed to be automatically raised or lowered into service position or stored position.

The primary object of the invention is to provide an extension table having a movable leaf normally concealed within the table top, and adapted to be automatically raised into a position flush with the upper surface of the table, when the two halves of the top are pulled apart for extending the table.

A further object is to furnish a table of this character, having a disappearing leaf adapted to automatically lower into a concealed position, when the two halves of the table top are moved toward each other.

A still further object is to provide an extension table of the disappearing leaf type, including means for limiting the movement of the extension leaf in various directions.

Another object is to furnish an extension leaf table of simple, inexpensive and durable construction, and one which will not be liable to get out of order, even after extensive use.

With the foregoing objects outlined and with other objects in view which will appear as the description proceeds, my invention consists in the novel features hereinafter described in detail, illustrated in the accompanying drawing, and more particularly pointed out in the appended claims.

Referring to the drawing, Fig. 1 is a bottom plan view of my improved table top with the elevatable leaf in lowered position.

Fig. 2 is a vertical longitudinal sectional view of the same.

Fig. 3 is a vertical transverse sectional view.

In the drawing, 10 indicates a table frame made up of side bars 11, and end bars 12, which are rigidly connected together and are supported by any suitable base construction, such as legs 13.

The bars 11 are provided at opposite sides with guides 14 which cooperate with complementary guides 15 on slide members 16 and

17. The members 16 are fixed to the movable

half A of the table top, while the members 17 are fixed to the other movable half B of the table top. This construction permits the two halves of the table top to be moved toward or away from each other, and when they are in the contracted position shown in the drawings, suitable dowel pins 18, at the inner end of one of the halves, enter apertures 19 in the inner end of the other half, as is customary in the ordinary extension table. The common type of extension table is constructed to permit one or more leaves to be inserted between the two halves when the latter are in extended position, and in my improved construction, such an extension leaf is shown at 20, but instead of having the same removable from the table top, it is permanently connected to the top, and will be raised or lowered when the two halves of the top are moved away from, or toward each other. The leaf is connected to the side bars 11 of the frame by means of link hinges 21, which prevent the leaf from moving lengthwise of the table top, and movement is prevented laterally by means of stop bars 22, which are secured to the leaf by any suitable means, such as screws 23. These stop bars cooperate with the side stiles 24 of the skirt of the table top.

For the purpose of raising the leaf when the halves of the top are moved away from one another, the leaf engages riser blocks 25 which are secured to the slide members 16 and 17 by any suitable means, such as screws 26. In the raising movement, the two halves of the table are caused to move in unison in opposite directions, due to the fact that one of the slide members 16, and one of the slide members 17, are provided with fixed racks 27 that mesh with a gear 28, rotatably mounted on one of the side bars 11 of the frame. It will therefore be understood that when either one of the halves of the table top is moved away from the other, the latter will be forced to move to the same degree, and consequently, the inclined portions 29 of the riser blocks will simultaneously cooperate with the opposite side edges of the leaf, to raise the latter into alignment with the upper surfaces of the two halves of the table top.

In order to hold the leaf steadily in its

elevated position, I mount a gate 30 by means of spring hinges 31, upon a stationary cross bar 32 which has its ends secured to the side bars 11 of the frame. The spring hinges have a tendency to move the gate into a vertical position, and in this position, the leaf 20 will rest upon the horizontal upper edge of the gate.

Another spring butt hinge 33 is mounted on one of the side edges of the gate, with one of its leaves extended outwardly beyond this edge of the gate, and this projecting hinge leaf cooperates with a pin 34 that projects laterally from one of the riser blocks 25. When the two halves of the top are pulled apart, to the limit of extension, the pin 34 will cause the projecting leaf of the spring hinge 33 to swing on its pintle, to allow the pin 34 to move past this hinge. After the pin has moved past the hinge 33, the spring of the latter will force its projecting leaf into the original position, and in such position, when the table halves are moved toward one another, the pin 34 will abut against the projecting leaf of the hinge 33, and act as a cam to swing the gate 30 from its vertical position, into the inclined position shown in Fig. 2.

In operating a table of this character, let us assume that the parts are in the positions shown in the drawing. At such time, the leaf 20 will be concealed within the table top, and will be resting upon the side bars 11. Now, if the two halves of the table are pulled apart, the inclines 29 will elevate the leaf 20 into its highest position, and the stop members 22 will come in contact with the under side of the two halves of the table top, and prevent any further upward movement, while the gate 30 will swing into vertical position, and its upper edge will engage the under side of the leaf, and prevent any downward movement. Then the two halves A and B will be moved toward one another to cause the dowel pins 18 of the table half B, to enter holes 35 in one edge of the leaf, and dowel pins 36 at the other edge of the leaf, to enter holes 19 in the edge of the half A. This will result in an unbroken extension top surface.

When the top is to be contracted and the leaf concealed, the two halves will first be pulled apart to the limit of extension, to separate the inner edges of the two halves from the side edges of the leaf, and to cause the pin 34 to move past the hinge 33. As the pin moves past the hinge, it will cause the projecting leaf of the latter to swing on its pintle to allow passage of the pin to the opposite side of the gate 30. Then, as the two halves are pushed toward each other, the pin 34 will engage the projecting leaf of the hinge 33, and as said hinge leaf cannot swing toward the half B, the pin will force the hinge 33 to move the gate 30 in a clock-

wise direction, as viewed in Fig. 2. Consequently, the leaf will be permitted to descend on the inclines 29 by gravity, until the leaf is lowered to its initial position, and then, as the two halves continue to move toward one another, their inner edges will overlap the leaf and eventually conceal the latter.

It might be mentioned at this point that the strength of the springs of the hinges 31 is insufficient to raise the leaf 20 without the assistance of the riser blocks 25, and, therefore, the gate 30 will not force the leaf 20 upwardly after the raised portions of the riser blocks have passed to opposite sides of the leaf.

From the foregoing, it is believed that the construction, operation and advantages of the invention may be readily understood, by those skilled in the art, and it is manifest that changes may be made in the details disclosed, without departing from the spirit of the invention, as expressed in the claims.

What I claim and desire to secure by Letters Patent is:

1. An extension table comprising a stationary frame including all of the supporting legs for the table, table top halves slidably mounted on the frame, means for causing the two halves to move in unison in opposite directions whenever the operator manipulates one of said halves, a normally concealed leaf mounted within the table top and movably connected to the frame, means for raising said leaf into alignment with the tops of said halves when the latter are moved away from one another, and movably mounted spring elevated gate cooperating with the leaf for holding the latter in elevated position.

2. An extension table comprising a stationary frame including all of the supporting legs for the table, table top halves slidably mounted on the frame, a normally concealed leaf mounted within the table top and movably connected to the frame, means for raising said leaf into alignment with the tops of said halves when the latter are moved away from one another, a gate pivotally mounted on the frame and adapted to secure the leaf in its elevated position, and spring means for moving the gate into securing position.

3. An extension table including a frame, table top halves slidably mounted on the frame, a normally concealed leaf mounted within the table top and movably connected to the frame, means for raising said leaf into alignment with the tops of said halves when the latter are moved away from one another, a gate pivotally mounted on the frame and adapted to secure the leaf in its elevated position, spring means for raising the gate, and means movable with one of the table halves for lowering the gate.

4. An extension table including a frame, table top halves slidably mounted on the frame, means for causing the two halves to

move in unison in opposite directions whenever the operator moves one of said halves, an elevatable leaf normally concealed within said halves, riser blocks movable with said halves and adapted, when the halves are moved apart, to raise said leaf, a gate cooperating with the leaf for holding the latter in elevated position, hinge means connecting the gate to the frame, spring means for raising said gate, and means movable with one of said halves for lowering the gate.

5. In an extension table of the concealed leaf type, table top halves movable toward and away from each other, a leaf normally concealed beneath said halves, means movable with the halves for elevating said leaf, a hinge gate adapted to be raised when the leaf is elevated, for securing the latter in elevated position, a spring pressed hinged 15 abutment projecting from the gate, and a cooperating abutment movable with one of said halves for causing the spring pressed abutment to lower the gate when said halves are moved toward each other.

25. 6. An extension table including a frame, table top halves slidably mounted on the frame, means for causing the two halves to move in unison in opposite directions whenever the operator moves one of said halves, an elevatable leaf normally concealed within said halves, riser blocks movable with said halves and adapted, when the halves are moved apart, to raise said leaf, a gate cooperating 30 with the leaf for holding the latter in elevated position, hinge means connecting the gate to the frame, spring means for raising said gate, means movable with one of said halves for lowering the gate, and stop members carried by the leaf and engageable with the under side of said halves to limit the upward movement of said leaf.

7. An extension table including a frame, table top halves slidably mounted on the frame, means for causing the two halves to move in unison in opposite directions whenever the operator moves one of said halves, an elevatable leaf normally concealed within said halves, riser blocks movable with said halves and adapted, when the halves are moved apart, to raise said leaf, a gate cooperating with the leaf for holding the latter in elevated position, hinge means connecting the gate to the frame, spring means for raising said gate, means movable with one of said halves for lowering the gate, and hinge means connecting said leaf to said frame.

8. An extension table comprising a stationary frame including the supporting legs for the table, table top halves slidably mounted on the frame, means for causing the two halves to move in unison in opposite directions whenever the operator manipulates one of said halves, an elevatable leaf normally concealed within said halves, means actuated 65 by the halves for elevating said leaf, a gate

mounted on the frame and cooperating with the leaf for holding the latter in elevated position, hinge means connecting the gate to the frame, springs means for raising said gate, and means movable with one of said halves for lowering the gate to permit the leaf to descend to a position below the tops of said halves.

9. An extension table comprising a stationary frame, table top members slidably mounted on the frame, means for causing said members to move in unison in opposite directions whenever the operator manipulates one of said members, an elevatable leaf normally concealed within said members, means actuated by said members for elevating said leaf, a hinged gate member mounted on the frame and cooperating with the leaf for holding the latter in elevated position, a spring hinge mounted on one of said members, and an abutment mounted on another one of said members and cooperating with the spring hinge for lowering said gate when the table top members are moved relatively to each other.

10. An extension table comprising a stationary frame, table top members slidably mounted on the frame, means for causing the table top members to move in unison in opposite directions whenever the operator manipulates either one of said members, an elevatable leaf normally concealed within said members, means actuated by movement of the members for elevating said leaf, a gate hingedly mounted on the frame and cooperating with the leaf for holding the latter in elevated position, a spring hinge secured to the gate and projecting from one edge of the latter, and an abutment pin mounted on one of said table top members, and adapted to engage and fold the spring hinge when the table top members are moved apart, said abutment pin being also arranged to engage the spring hinge and to force the gate into lowered position when the table top members are moved toward each other.
